UNITED STATES PATENT OFFICE.

ROBERT A. GRIEVE, OF KEARNEY, NEBRASKA.

BARBER'S CABINET.

934,521.

Specification of Letters Patent. Patented Sept. 21, 1909.

Application filed January 4, 1909. Serial No. 470,675.

To all whom it may concern:

Be it known that I, ROBERT A. GRIEVE, a citizen of the United States, residing at Kearney, in the county of Buffalo and State 5 of Nebraska, have invented certain new and useful Improvements in Barbers' Cabinets, of which the following is a specification.

My invention relates to barbers' cabinets, and the object thereof is to provide a compact and inexpensive construction to hold, 10 in a readily accessible position, those tools and articles used most frequently in this character of work.

In the accompanying drawing, illustrating 15 my invention, and forming a part of this specification, Figure 1 is a perspective elevation of my improved cabinet. Fig. 2 is a transverse vertical sectional view taken therethrough to illustrate the internal operating devices, and, Fig. 3 is a fragmentary detail view illustrating the strop handle holder.

In the embodiment of my invention, as shown, I provide a cabinet comprising 20 spaced side walls 1 and 2, having their upper edges forwardly downwardly stepped, and connected by means of a top plate or wall 3, conforming to the said upper edges whereby to form shelves 4, 5 and 6 for the reception 25 of tonics, waters, cosmetics, and a comb and brushes, the shelf 5, having a series of circular openings 7, for the reception of cosmetic jars to be set down therein.

The top plate or wall 3, at its lower forward edge, is provided with a downturned ledge 8^a, extending downwardly between the forward edges of the side walls 1 and 2. The lower straight horizontal edges of the side walls 1 and 2 are connected by a lower 35 wall or base plate 8, having an upturned ledge 8^a at its front edge. The rear edges of the top and bottom walls 3 and 8, and side walls 1 and 2, are suitably secured to a rear wall 9, extending sidewise beyond said side 40 walls, whereby to support, between its extending portions and said walls, superposed bracket plates 10 and 11, the lower plates 10 of which are flat for the reception of hair clippers and such articles, while the upper 45 plates are formed in vertically offset portions constituting shelves 12 and 13 supplemental to, and having the same functions as, shelves 4, 5 and 6.

Secured to the outer surface of the side 50 wall 1, is a bracket 14, tapering rearwardly beneath the lower bracket plate 10 thereof,

and forming a housing for the reception of scissors. A similar housing 14, may, if it be deemed expedient, be secured upon the outer surface of the opposite side wall 2.

60

Mounted to slide horizontally within the side walls 1 and 2, entering between the vertical front edges thereof, are supported drawers 15 and 16, the upper one 15 of which is relatively small, being adapted for 65 the reception of razors, and being provided with a vertically swinging cover 17 hinged along the lower forward edge of the top plate or wall 3. The lower drawer 16 embodies an upper tray 18, having a plurality 70 of cup-shaped receptacles 19, for the reception of coins, and carrying therein below said tray, a paper roll 20, discharging its paper, for use in shaving, through a discharge mouth 21 in the front wall of said drawer. The drawer 16 is provided upon the outer surface of its rear wall 22, with a bracket 23, in which is secured the rear 75 end of a retractile coil spring 24, extending forwardly along the base of said drawer and secured at its forward end to a screw plug 25, adjustably mounted through the upturned ledge 8^a of the base plate 8. In its closed position, the drawer 16 stretches 80 spring 24 and is secured by a horizontal latch bar 26, intermediately pivoted upon a stationary bracket 27, and provided rearwardly of its pivot with a downwardly projecting latch piece 28 to engage the above 85 mentioned wall 22, as clearly shown in Fig. 90

2. The rear end of said latch bar is connected to the rear wall 9, by means of a retractile spring 29, serving to pull downwardly upon said latch bar end at all times, while the forward end thereof is pivotally 95 secured to the lower end of a vertically depressible operating rod 30, having its offset headed upper end 31, projecting forward through a vertically elongated slot 32, in the top plate or wall 3. The operation will thus 100 be clear.

Mounted upon a shaft 33, extending between the side walls 1 and 2 are one or more reels 34, each controlled by a spring 35, and having razor strops 36 wound thereabout, which strops extend outwardly through openings in the downturned ledge 39 of the top plate or wall 3, and are provided, upon their outer ends with handles 37 having circular peripheral grooves 38, 110 and connected to said strops to swing sidewise with relation thereto. The side walls

1 and 2 are adjacent their forward vertical edges and in the same horizontal plane as the openings through which the strops 36 pass, with spaced forwardly projecting spring 5 fingers 39, secured thereto by a rivet, screw, or the like 40, and designed to receive and hold the strop handles 37, by engagement with their grooves 38, when said handles have been swung sidewise, as clearly shown 10 in Fig. 1. The strops 36, in their length, pass beneath and against rollers 41, journaled to rotate in brackets 42, depending from, and secured to, a portion 43 of the top plate or wall 3, forming a supplemental 15 base beneath the shelf 5, on which the cosmetic jars may rest, and to which portion 43 is also secured the pivot bracket 27 of the latch bar 26.

Having fully described my invention, I 20 claim:

1. In a barber's cabinet, the combination of side walls having stepped upper edges, and a top wall extending between the said upper edges and conforming to the stepped 25 relation thereof, to form shelves, and provided in one of said shelves, with openings for the reception of cosmetic jars, said top wall having a portion extending below said last named shelf to form a rest for the said 30 jars, substantially as described.

2. In a barber's cabinet, the combination of spaced side walls, a top wall connecting the upper edges of said side walls and provided with a forward down-turned ledge, 35 having slotted openings therein, a drawer slidably mounted between said side walls, a shaft extending between said side walls, spring controlled reels mounted on said shaft, and strops wound upon said reels and 40 extending through said ledge openings above

said drawer and provided with exterior handles, substantially as described.

3. In a barber's cabinet, the combination of spaced side walls, a top wall, connecting the upper edges of said side walls and provided with a forward down-turned ledge, 45 having slotted openings therein, a drawer slidably mounted between said side walls, a shaft extending between said side walls, spring controlled reels mounted on said shaft, and spring clips carried by said side walls to hold said handles out of the path of movement of said drawer, substantially as described.

4. A barber's cabinet comprising spaced 55 side walls having their upper edges stepped for wardly and downwardly, a top connecting said upper edges of said side walls, and conforming thereto to provide shelves, a bottom wall connecting the lower edges of said 60 side walls, a rear wall connecting said top and bottom walls, and said side walls, and extending sidewise beyond the latter, superposed brackets forming shelves, secured between said side walls and said rear walls, a 65 bracket secured to one of said side walls, forming a housing for scissors, and superposed drawers slidable between said side walls, one of said drawers embodying a coin tray, and a shaving paper magazine below 70 said tray, and having a discharge mouth for the paper from said magazine, substantially as described.

In testimony whereof I affix my signature in presence of two witnesses.

ROBERT A. GRIEVE.
